UNITED STATES PATENT OFFICE

165,043

PENDANT MAGNIFYING LENS

Robert W. Ankney, Walton Hills Village, Ohio

Application May 5, 1951, Serial No. 15,079

Term of patent 3½ years

(Cl. D57—1)

To all whom it may concern:

Be it known that I, Robert W. Ankney, a citizen of the United States, residing at 169 Morningside Drive, Walton Hills Village, State of Ohio, have invented a new, original, and ornamental Design for a Pendant Magnifying Lens, as shown in the accompanying drawing, wherein:

Fig. 1 is a front plan view in closed position of a pendant magnifying lens of my invention;

Fig. 2 is a perspective view of the design of Fig. 1;

Fig. 3 is a front view of the design of Figs. 1 and 2, the view showing the design in open position.

I claim:

The ornamental design for a pendant magnifying lens, as shown.

ROBERT W. ANKNEY.
